UNITED STATES PATENT OFFICE

99,623

DESIGN FOR DISPLAY BOTTLES AND CONTAINER THEREFOR

Robert B. Karoff, Chicago, Ill.

Application January 13, 1936, Serial No. 60,551

Term of patent 3½ years

To all whom it may concern:

Be it known that I, Robert B. Karoff, a citizen of the United States, residing at Chicago, in the county of Cook and State of Illinois, have invented a new, original, and ornamental Design for Display Bottles and Container Therefor, of which the following is a specification, reference being had to the accompanying drawing, forming part thereof.

In the drawing,

Fig. 1 is a perspective view of the display bottles and container therefor, showing my new design, the container being shown in open position with the bottles displayed therein.

Figure 2 is a view partly in cross section and partly in elevation showing the container with the cover in place and the display bottles therein.

My design as shown comprises a set of ornamental bottles intended for perfumes or the like, which bottles are mounted in the base of the package as shown, for display purposes and may be enclosed by placing the top of the container in closed position as will be seen from Figure 2.

I claim:

The ornamental design for display bottles and container therefor, substantially as shown and described.

ROBERT B. KAROFF.
